United States Patent Office.

GEORGE L. WOODS, OF NEWBURYPORT, MASSACHUSETTS.

Letters Patent No. 79,885, dated July 14, 1868.

IMPROVEMENT IN WINDLASS.

The Schedule referred to in these Letters Patent and making part of the same.

Be it known that I, GEORGE L. WOODS, of Newburyport, in the county of Essex, and State of Massachusetts, have invented a new and improved Windlass, of which the following is a full, clear, and exact description, reference being had to the accompanying drawings, making a part of this specification, in which—

Figure 1 is a vertical longitudinal section of a windlass embodying my invention.

Figure 2 is an end elevation of the same, showing its parts in perspective.

The object of my invention is to furnish a windlass by which a chain or cable shall be wound in with a steady continuous motion.

The severe strain upon the cable and windlass, resulting from the present method of winding by successive starts and rests, it is desirable to avoid.

The loss of power besides, by winding in this manner, is considerable, since the heavy members of the machine are brought completely to rest between the impulses, thus entirely losing their acquired momentum.

The invention consists in a combination of mechanism by which the turning of a capstan causes the revolution of two wheels, upon which are cranks, connected by link with ratchets, which actuate the windlass. The cranks referred to are upon wheels independent of each other, and so arranged that both the links can never be simultaneously at rest. The capstan may be readily disengaged and employed for other purposes when desirable.

Referring to the drawings, the parts marked *a* are portions of the deck and timbers of a vessel; *a'* is the foot of the bowsprit; *c* is an ordinary capstan, which turns about a vertical spindle, *d*, supported upon a step, *d'*. A sliding key, *e*, upon the shaft *d*, which may be moved up or down easily, by employing a suitable instrument, introduced after the removal of the capstan-cover, permits the capstan *c* and the shaft *d* to engage together or to be disengaged, as required.

By the employment of spur-wheels, motion is communicated from the shaft *d* to the shaft *d''*. The spur-wheels *f* and *f'* are fixed upon the shafts *d* and *d''* respectively. By a suitable arrangement of the mechanism, mechanical power may be exchanged for velocity, or *vice versa*.

To the vertical shaft *d''*, besides the spur-wheel *f'*, a bevel-wheel, *g*, is attached. The bevel-wheel *g* engages with two similar bevel-wheels, *h* and *h'*, which are independent of each other, and are maintained in their positions in a suitable manner.

Upon the outer face of each wheel *h* *h'* is a crank-pin, *k*, each of which is connected by a link, *l*, with a ratchet, *l'*, constructed and combined with the cylinder *r*, in the usual manner.

The revolution of the wheel *g* causes the bevel-wheels *h* and *h'* to revolve in contrary directions, but the positions of the two crank-pins *k* are such that the two links *l* never pass a dead-point simultaneously; therefore the ratchets *l'* are, the one or the other, constantly in action. The cylinder *r* is braced and kept from counter-revolution by a detent in the customary way.

s *s'* represent the levers which cause the ratchets *l'* to advance and recede at successive intervals, when combined with the links *S*', as in the common ship-windlass. These levers may be employed in case the combination specified is from any cause disabled.

What I claim as my invention, and desire to secure by Letters Patent, is—

The arrangement of the capstan *c*, shaft *d*, gears *f* *f'*, and the bevel-gears *g* *h* *h'*, in connection with the windlass *r*, when constructed and operated as and for the purpose set forth.

In testimony whereof, I have signed my name to this specification in the presence of two subscribing witnesses.

GEO. L. WOODS.
